CLAIM

The ornamental design for a surgical handpiece, as shown and described.

DESCRIPTION

FIG. 1 is a front, top, right-side perspective view of a surgical handpiece;

FIG. 2 is a rear, bottom, left-side perspective view thereof;

FIG. 3 is a right-side view thereof;

FIG. 4 is a left-side view thereof;

FIG. 5 is a front view thereof;

FIG. 6 is a rear view thereof;

FIG. 7 is a top view thereof; and,

FIG. 8 is a bottom view thereof.

The dot-dot broken lines in the drawings depict portions of the surgical handpiece that form no part of the claimed design. The dash-dot broken lines in FIGS. 1, 2, 5, and 6 illustrate the bounds of the claim and form no part of the claimed design.
